UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,182,352.

Specification of Letters Patent.

Patented May 9, 1916.

Application filed September 9, 1914. Serial No. 860,825.

To all whom it may concern:

Be it known that I, CORNELIUS B. CORCORAN, a citizen of the United States, residing in borough of Bronx, in the county of Bronx, city and State of New York, have invented certain new and useful Improvements in Type-Writing Machines, of which the following is a specification.

This invention relates to typewriting machines, and is more particularly directed to the paper feeding mechanism thereof, the main object being to provide means whereby a large number of work-sheets, having together a bulk or thickness not conveniently accommodated by the feeding means ordinarily provided, may be readily received between the paper apron and platen, and advanced around the platen by the feed rolls.

Certain difficulties have barred the way to the adaptation of existing methods for the purpose in view, and the paper-receiving and feeding devices at present employed have been found to require re-arrangement, and to be equipped with novel means of actuation, to be readily capable of efficiently serving the desired function. The desired object has therefore been accomplished in the present invention, by providing a common pivotal support for the carriers of the rear and front series of feed rolls, and that support rendered movable to and from the platen to alternately press the two series of feed rolls together against the platen and withdraw them therefrom, the separate series of feed roll carriers on their common pivotal support having a self-balancing action which enables both series of feed rolls, when pressed toward the platen, to grip interposed work-sheets thereto under the exercise of equal pressure by both series of rolls, thereby insuring regular feeding of a pile of work-sheets in their advance around the platen.

The work-sheets are directed to the rear feed rolls, and from the rear feed rolls to the front feed rolls, by a paper apron which is hinged to the paper table to be capable of movement with the feed rolls to and from the platen for coöperation therewith.

It being desirable to produce a roll-supporting structure of light weight while employing sufficient tension to press the feed rolls serviceably toward the platen, I provide a number of pressure springs at inter-

vals along said structure in order that the tension under which the rolls are pressed to the platen may be equally distributed throughout the length of the line of application, and I also provide means for adjusting the tension of the springs in order that the pressure may be properly regulated.

Other features and advantages will hereinafter appear.

In the accompanying drawings, Figure 1 is a perspective elevation of a platen and platen frame, showing my improved arrangement of feed rolls and paper apron. Fig. 2 is a side elevation, partly in section, of the same, showing the feed rolls and paper apron as applied to the platen. Fig. 75 3 is a similar, fragmentary view, showing the feed rolls and apron released from the platen. Fig. 4 is an enlarged sectional detail view of one of the tension-adjusting springs. Fig. 5 is a detail view of the parts 75 forming the hanger for the feed rolls, as disassembled.

The invention is herein illustrated as applied to an Underwood typewriting machine having a platen 1 with an axle 2 journaled 80 in the ends 3 of the platen frame, the line-spacing mechanism also being shown, including the line-space wheel 4, pawl 5 and spring-returning slide 6. The platen frame is also provided with a wheel or roller 7, 85 whereby it may run along the usual case-shift supporting rail 8.

To fulfil the purpose of the invention, of admitting a multiplicity of work-sheets between the paper apron and the platen, to be 90 fed around the platen by the feed rolls, I have shown the paper apron 9 as hinged to the lower end of the paper table 10, said paper apron swinging downwardly by its own gravitation to be in a receptive position with the feed rolls, as 11, 12; said paper apron in that receptive position being supported as by the feed roll supports.

The feed rolls 11 and 12 are mounted as is usual along rods as 13, and 14, and said rods 100 may be carried respectively at the outer ends of arms 15 and 16, said arms being integral or rigidly connected one with another and mounted at an intermediate point upon a floating, flexible rod 17, which thus forms a 105 common fulcrum for the arms 15 and 16, and consequently for the support of the rear and front rolls 11 and 12. In the drawing,

the arms 15 and 16 are shown as comprising a curved hanger or member which, with the rods 17, 13 and 14, forms what may be termed a cradle hanger, the rods 13 and 14 being supported from the rod 17 in a manner to present the rolls 11 and 12 together to the platen, and to release them together from the platen.

5 The rod 17 has connecting arms 18, which are rigidly mounted upon a rock shaft 19 that is journaled in bearings 20, respectively at the opposite ends of the platen frame, said rock shaft 19 at one end having a hub 21 with an extending arm 22 to which 10 is pivoted a link 23, said link having pivotal engagement at its opposite end with an arm 24 carried by a shaft 25 journaled in bearings 26 in the platen frame, and having an operating lever 27 with finger-piece 28.

15 20 Carried from the opposite ends of the platen frame, centrally beneath the cradle hanger, is a longitudinal brace, which may be in the form of an angle strip 29, whose purpose is to support said cradle hanger and to stiffen the operative connections therefor. Thus the rock shaft 19 is braced throughout its length by a series of brackets 30 which are rigidly connected to said brace 29 at one end and at their opposite 25 ends have journal bearings to receive and carry said rock shaft. The cradle hanger is tensionally supported from said brace 29, the means whereby it is so supported consisting of coiled springs 31 surrounding 30 threaded studs 32, which extend from collars 33 mounted upon the rod 17, said threaded studs being guided within hollow mounts or seats 34, which are secured upon rail 29 and engage the opposite ends of the 35 threaded studs 32. Each threaded stud 32 has a nut, as 35, thereon, which nut may be either a thumb nut, or a nut with faces or other provision for handling with tools, the purpose of said nuts being to vary the tension of the springs 31.

40 45 In order to regulate the tension exercised upon the cradle hanger throughout its length, the springs 31, with associated parts, provided at suitable intervals along rod 17, and operating from the rigid support provided by brace 29, serve, when regulated, to press evenly against rod 17 to thereby cause the two series of feed rolls to be urged under uniform pressure against the platen, this effect being obtained 50 on account of the non-rigid or flexible character of the cradle hanger. It is evident that if the support for the said feed rolls were to be made of sufficient rigidity to avoid liability of springing and to insure 55 efficient engagement of all the rolls carried thereby along its length with the platen, the structure necessary for that purpose would be too cumbersome to permit of practical employment, and I have resorted to the 60 means herein described entailing the use of

65 a strong though non-rigid support of relatively light weight and moderate compass, equipping the same with springs whose tension may be varied, and whose tension is directed upon the support from a rigid base, 70 in this way achieving the purpose along extended lines of feed rolls of directing them under uniform tension against the platen.

75 The arm 24 and link 23 comprise a toggle joint, its connection through arm 22 with rock shaft 19 being such that the toggle members are at an angle to each other when the feed rolls are pressed by their springs against the platen, and the action of straightening the toggle, in the operation of 80 lever 27 forces said feed rolls away from the platen against the tension of their springs to afford the relatively large clearance required for the introduction of a number of work-sheets.

85 Suitable stop means are provided for the toggle joint to arrest its movement and detain the feed rolls in their released position, such means being here shown as a stop pin 36 upon the platen frame in the path of the 90 arm 24, to prevent movement of the toggle joint beyond the straightened position. It will be seen that upon the application of slight pressure upon the lever 27, in the opposite direction, to "break" the toggle joint, 95 the pressure of springs 31 will at once impel the feed rolls to their operative position.

100 The arms 18, which carry the rod 17 and are themselves fast upon the rock shaft 19, may each have a hub 37 with a shouldered portion 38, a separate shouldered sleeve or hub portion 39, which may be secured to the rock shaft 19, as by a set screw 40, engaging with said shouldered hub 37 at one side thereof while the opposite side of said 105 shouldered hub 37 may abut against a bracket 30, whereby said arm 18 is confined upon the rock shaft 19 and caused to rock therewith.

110 The apron 9, which, as stated, swings from its hinged engagement with the paper table 10, moves by gravity to the released position with a corresponding movement of the feed rolls, and, as thus released, it is supported by the cradle hanger, as upon the 115 adjacent surfaces of the arms 15 and 16, which supports, when the feed rolls are pressed into engagement with the platen, carry said paper apron with them into its operative position in which it directs the 120 work-sheets being advanced by the pressure rollers.

125 Aside from the saving in bulk and weight in the formation of a non-rigid support for the feed rolls, an inherent advantage in such structure, especially where employed with long platens, as used for billing machines, lies in its ability by aid of the adjustable tension devices aforesaid, to insure the application of the feed rolls to the 130

5 platen throughout its length under uniform pressure; whereas, when the roll-holding structure is rigid, the rolls carried thereby may not always bear equally against the platen, resulting, especially in the case of platens, of great length, in causing the work-sheets to be advanced unevenly.

10 Variations may be resorted to within the scope of the invention, and portions of the improvements may be used without others.

15 Having thus described my invention, I claim:

1. In a typewriting machine, the combination with a revoluble platen, of two series 20 of feed rolls arranged along said platen arms upon which said rolls are mounted, said arms having a common support movable to carry them together to and from the platen, and adjustable spring means for pressing said support evenly toward the platen throughout its length.

25 2. In a typewriting machine, the combination with a revoluble platen, of two series of feed rolls arranged along said platen arms upon which said rolls are mounted, said arms having a common support movable to carry them together to and from the platen, while leaving said series of spring rolls free to accommodate themselves under 30 even pressure against the platen.

35 3. In a typewriting machine, the combination with a revoluble platen, of feed rolls arranged along said platen, arms carrying said feed rolls, a floating support therefor whereby said arms and rolls are movable to and from said platen, and adjustable spring means bearing upon said support at intervals throughout its length, causing said feed rolls to coöperate under uniform pressure with said platen.

40 4. In a typewriting machine, the combination with a revoluble platen, of feed rolls arranged along said platen, arms for said feed rolls, a floating non-rigid support on which said arms are mounted, means whereby they are movable to and from said platen, a rigid brace, and adjustable spring means upon said brace bearing at intervals upon said support throughout its length, 50 causing said feed rolls to coöperate under uniform pressure with said platen.

45 5. In a typewriting machine, the combination with a revoluble platen, of feed rolls arranged along said platen, means carrying said rolls, a flexible support for said carrying means, means whereby said flexible support is movable to and from said platen, a rigid brace, and adjustable spring means upon said brace bearing at intervals upon 55 said support throughout its length, causing said feed rolls to coöperate under uniform pressure with said platen.

60 6. In a typewriting machine, the combination with a revoluble platen, of two parallel series of feed rolls arranged along a

common support on which they are free to rock oppositely, said support being movable to carry said series of feed rolls together to and from the platen, a rigid brace, and adjustable spring means for pressing said support evenly toward the platen throughout its length. 70

7. In a typewriting machine, the combination with a revoluble platen, of a cradle hanger comprising parallel rods each carrying a series of feed rolls, spacing arms in which said rods are mounted, an intermediate rod pivotally supporting said spacing arms, a rigid brace, and adjustable spring means for pressing said cradle hanger evenly toward the platen throughout its length. 75

8. In a typewriting machine, the combination with a revoluble platen, of feed rolls arranged along said platen, a non-rigid support therefor, means whereby they are movable together to and from said platen, spring means to urge said support toward the platen, a rigid brace, and means to move said support to a position of detention 90 with the rolls released from the platen.

9. In a typewriting machine, the combination with a revoluble platen, of feed rolls arranged along said platen, a non-rigid support therefor, means whereby they are movable together to and from the platen, a rigid brace, adjustable spring means to urge said support evenly toward the platen throughout its length, and means to move said support to a position of detention 95 with the rolls released from the platen. 100

10. In a typewriting machine, the combination with a revoluble platen, of feed rolls arranged along said platen, arms carrying said rolls, a non-rigid support for said arms, means whereby said support, arms and rolls are movable together to and from said platen, spring means to urge said support toward the platen, and trip return means to move said support to a position of detention 110 with the rolls released from the platen. 105

11. In a typewriting machine, the combination with a revoluble platen, of feed rolls arranged along said platen, arms carrying said rolls, a non-rigid support for said arms, means whereby said support, arms and rolls are movable together to and from said platen, spring means to urge said support toward the platen, and a toggle device to move said support to a position of detention 120 with the rolls released from the platen. 115

12. In a typewriting machine, the combination with a revoluble platen, feed rolls arranged along said platen, arms carrying said rolls, a non-rigid support for said arms, means whereby said support, arms and rolls are movable together to and from said platen, a rigid brace, spring means upon said brace to urge said support toward the 130

- 1 platen, and means to move said support to a position of detention with the rolls released from the platen.
13. In a typewriting machine, the combination with a revoluble platen, of feed rolls arranged along said platen, arms carrying said rolls, a non-rigid support for said arms, means whereby said support, arms and rolls are movable together to and from said platen, a rigid brace, adjustable spring means upon said brace to urge said support evenly toward the platen throughout its length, and means to move said support to a position of detention with the rolls released from the platen.
14. In a typewriting machine, the combination with a revoluble platen, of parallel series of feed rolls therefor, a common support whereby said series of rolls are movable together to and from the platen, a rigid brace having springs urging said support toward the platen, a rock shaft having arms engaging said support, and means for operating said rock shaft to swing said roll support and thus release the rolls from the platen.
15. In a typewriting machine, the combination with a revoluble platen, of parallel series of feed rolls therefor, a common support whereby said series of rolls are movable together to and from the platen, springs urging said support toward the platen, a brace extending lengthwise of the platen, a rock shaft having arms engaging said support, supporting brackets upon said brace for said rock shaft, and means for operating said rock shaft to swing said roll support and thus release the rolls from the platen.
16. In a typewriting machine, the combination with a revoluble platen, of parallel series of feed rolls therefor, a common support whereby said series of rolls are movable together to and from the platen, springs urging said support toward the platen, a rock shaft having arms engaging said support, and trip-return means for operating said rock shaft to swing said roll support and thus release the rolls from the platen.
17. In a typewriting machine, the combination with a revoluble platen, of parallel series of feed rolls therefor, a common support whereby said series of rolls are movable together to and from the platen, a brace extending lengthwise of the platen, a series of pressure springs arranged at intervals between said brace and support, and means for adjusting the tension of said springs in the application of even pressure upon said support.
18. In a typewriting machine, the combination with a revoluble platen, of feed rolls arranged along said platen, supports for said feed rolls, said supports movable toward and from said platen, a paper apron supported by said roll supports movable with said feed rolls toward the platen, and adjustable spring means for pressing said rolls evenly against the platen throughout their lines of engagement therewith.
19. In a typewriting machine, the combination with a revoluble platen, of feed rolls arranged along said platen, supports for said feed rolls, said supports movable toward and from said platen, a paper table, a paper apron hinged thereto, supported by said roll supports and movable with said feed rolls toward the platen, and adjustable spring means for pressing said rolls evenly against the platen throughout their lines of engagement therewith.
20. In a typewriting machine, the combination with a revoluble platen, of two series of feed rolls therefor, a common support movable to carry said series of feed rolls together to and from the platen, a paper apron engaging with said support to move therewith toward the platen, and a rigid brace provided with spring means for pressing said rolls against the platen throughout their lines of engagement therewith.
21. In a typewriting machine, the combination with a revoluble platen, of two series of feed rolls therefor, a common support movable to carry said series of feed rolls together to and from the platen, a paper table, a paper apron hinged thereto and engaging with said support to move therewith toward the platen, and a rigid brace provided with spring means for pressing said rolls against the platen throughout their lines of engagement therewith.
22. In a typewriting machine, in combination, a revoluble platen, feed rolls, a spring mounted flexible floating shaft for said feed rolls and a rigid brace against which the pressure of said springs is exerted.
23. In a typewriting machine, in combination, a revoluble platen, sets of feed rolls arranged to coöperate therewith, hangers in which said sets of feed rolls are mounted, a flexible shaft on which said hangers are mounted, a rigid brace, and springs acting between said brace and flexible shaft, to press the latter toward the platen.
24. In a typewriting machine, in combination, a revoluble platen, sets of feed rolls arranged to coöperate therewith, hangers in which said sets of feed rolls are mounted, a flexible shaft on which said hangers are mounted, a rigid brace, springs acting between said brace and said flexible shaft, to press the latter toward the platen, a rock shaft, arms rigid on said rock shaft engaging said flexible shaft and means for turning said rock shaft, to withdraw said flexible shaft and pressure rolls from platen engagement.
25. In a typewriting machine, in combination, a revoluble platen, sets of feed rolls ar-

ranged to coöperate with said platen, curved hangers in the ends of which said sets of feed rolls are mounted, a flexible shaft passing through said curved hangers between the ends thereof, collars on said shaft, a rigid brace, beneath said flexible shaft, and springs resting on said brace and engaging said collars.

26. In a typewriting machine, in combination, a revoluble platen, sets of feed rolls arranged to coöperate therewith, hangers in which said sets of feed rolls are mounted, a flexible shaft on which said hangers are mounted, a rigid brace, springs acting be-

tween said brace and said flexible shaft, to 15 press the latter toward the platen, a rock shaft, arms rigid on said rock shaft engaging said flexible shaft, brackets mounted on said brace in the upper ends of which brackets, said rock shaft is mounted, and means 20 for turning said rock shaft, to withdraw said flexible shaft and pressure rolls from platen engagement.
